UNITED STATES PATENT OFFICE.

PHILIP H. RAIFORD, OF ST. MARY'S, GEORGIA.

IMPROVEMENT IN BRUSHES.

Specification forming part of Letters Patent No. 176,682, dated April 25, 1876; application filed October 13, 1875.

To all whom it may concern:

Be it known that I, PHILIP H. RAIFORD, of St. Mary's, in the county of Camden and State of Georgia, have invented certain new and useful Improvements in Brushes and Brooms, of which the following is a specification; and I do hereby declare that in the same is contained a full, clear, and exact description of my said invention, reference being had to the accompanying drawing, and to the letters of reference marked thereon.

My invention relates to a brush or broom formed of a series of notched frames or holders, into which the flexible material constituting the brush proper is inserted and secured, as hereinafter described. In the drawing annexed hereto I have shown the said flexible material to consist of certain portions of the "saw" or "scrub" palmetto, which is found to be well adapted for the purpose, although other kinds of material may be employed.

In the further description of my invention which follows, due reference must be had to the accompanying drawing, forming a part of this specification, and in which—

Figure 1 is a side view of one of the series of notched holders, showing the position of and manner of securing the palmetto leaves therein. Fig. 2 is a top view of a complete brush, and Fig. 3 is a side view of the same.

Similar letters of reference indicate similar parts in all the figures.

A A are the notched holders, and B is a follower board, adapted to close the notches in the last of the series of holders used in the construction of the brush. C C are the pieces

of the flexible material secured within the notches in the holders.

The frames or holders having been prepared, the manner of constructing the brush or broom is as follows: The sections of the material to be used are compressed edgewise and inserted in the notches in the holders, and secured therein by means of the nails *a* until a sufficient number of the filled frames have been placed together to give the desired thickness of the brush, when the follower-board B is then added and the whole fastened together by means of nails or screws.

My improved brush or broom is cheaply made, as the frames are of a common size and shape, and the thickness of the brush dependent only upon the number of the holders employed in its construction. The material can be cut to any desired length to suit the different purposes for which brushes of this description are applicable.

Having thus described my invention, what I claim as new, and desire to secure by Letters Patent of the United States, is—

The combination of a series of notched holders, A A, a series of bunches or sections, C C, of flexible material, and a follower-board, B, with a series of fastening-pins, *a a*, all arranged substantially as and for the purpose specified.

In testimony whereof I have hereunto subscribed my name this 30th September, in the year of our Lord 1875.

PHILIP H. RAIFORD.
